FOREIGN PATENT DOCUMENTS

EM 000729306-0004 * 6/2007

Primary Examiner — Thomas Johannes*Assistant Examiner* — Catherine Posthauer(74) *Attorney, Agent, or Firm* — Sheridan Ross, PC(57) **CLAIM**

The ornamental design for a spray cap for aerosol containers, as shown and described.

DESCRIPTION

FIG. 1 is an enlarged perspective view of a spray cap for aerosol containers showing our new design;
FIG. 2 is a front elevation view thereof;
FIG. 3 is a rear elevation view thereof;
FIG. 4 is a left elevation view thereof;
FIG. 5 is a right elevation view thereof;
FIG. 6 is a top plan view thereof;
FIG. 7 is a bottom plan view thereof;
FIG. 8 is an enlarged perspective view thereof, in a second position of use;
FIG. 9 is a front elevation view thereof;
FIG. 10 is a rear elevation view thereof;
FIG. 11 is a left elevation view thereof;
FIG. 12 is a right elevation view thereof;
FIG. 13 is a top plan view thereof; and,
FIG. 14 is a bottom plan view thereof.

The broken lines are shown for the purpose of illustrating portions of the article that form no part of the claimed design.

1 Claim, 8 Drawing Sheets---
